UNITED STATES PATENT OFFICE.

FRANK B. STRATFORD, OF JERSEY CITY, NEW JERSEY.

APPARATUS FOR TREATING FIBROUS MATERIAL.

Application filed July 11, 1917. Serial No. 180,029.

To all whom it may concern:

Be it known that I, FRANK B. STRATFORD, a citizen of the United States, residing at Jersey City, in the county of Hudson and 5 State of New Jersey, have invented certain new and useful Improvements in an Apparatus for Treating Fibrous Material, of which the following is a specification, reference being had therein to the accompanying drawing.

10 My invention relates to improvements in the treatment of hemp, jute, flax or other fibrous material such as may be used in the manufacture of oakum and other materials, 15 and has particular reference to an apparatus for separating and impregnating the hemp. The hemp is usually received in bales which have been compressed under high pressure and it requires considerable hard labor to 20 open and prepare the hemp for use and for subsequent treatment such as in the case where oakum is to be manufactured. To this end one of the objects of my invention is to release the bales of hemp from the binders 25 and then subject the same to a proper mixture of tar which impregnates the hemp as the released bale expands after which it is passed to suitable heating chambers.

In the accompanying drawing marked 30 Fig. 1, I have illustrated in perspective with parts broken away, a suitable apparatus for carrying out a preferred application of my invention, Fig. 2 illustrates suitable apparatus for predetermining the amount of tar to 35 be used in each bale.

2 indicates a suitable chamber provided with tracks such as 3 and a cable such as 4 for conveying suitable cars such as 6 therethrough, and 7 indicates the inlet doors and 40 8 the outlet door therefrom, 9 indicates a suitable partition as hereinafter more fully referred to.

10 indicates a barrel of tar or other suitable material which may be rolled along the 45 floor 11 and after the bung has been removed therefrom, the barrel may be rolled over a suitable hole or outlet 12 through the floor connected by the pipe 13 which supplies the tank 14 with the tar from the barrel. 15

50 indicates a suitable pipe connected with an air pressure tank 16 which may be supplied with air from a suitable motor pump such as 17, so that the compressed air pressing down upon the tar within the tank 14 drives 55 the same upwardly through the outlet pipe 17', it being of course understood that a suit-

able valve such as 18 may be provided, so that after the tar from the barrel 10 has passed into the tank 14, the pipe 13 may be shut off to prevent driving the tar back 60 from the tank 14 into the barrel 10, thus causing the tar to pass upwardly into the heating chamber 18' provided with suitable coils such as 19 fed by the steam pipe 20 from the radiator 21. 14' indicates a suitable valve in the pipe 17'.

After a bale of hemp has been released from its ties or binders, it is dropped into a car 6 which is sufficiently large inside to allow for the separation and expansion of 70 the bale. This car is then pushed or drawn rightwardly through the doors 7 into the chamber 21. The tar from the tank 14 having been fed into the heating chamber 18' is now sufficiently liquefied to feed downwardly through the tube 22 subject to the valve 22' into a suitable discharging device such as 23—24 from which it may be sprayed or discharged upon the bale 25 in the car 6, the heat of the liquid tar thereupon causes 80 the initial expansion and separation of the laminations of hemp after which the car is pushed or drawn rightwardly as by the cable 4 to the position indicated by the car marked 26 into the heating chamber 2 beyond the 85 partition 9 and as another car of hemp is introduced into the chamber 21, the first car then occupies the position of the car indicated by the reference character 27, and then to the position occupied by the car indicated 90 by the reference character 28, and so on until each car is successively passed out of the oven 2 through the door 8 and during its passage through the oven the hemp is further heated by the steam coils 21 thus further 95 separating and loosening the hemp and further impregnating the same with the liquid tar thereupon.

In this way the hemp is separately and thoroughly saturated or impregnated without the necessity of manual labor or mechanical effort in separating the originally tightly compressed bale, thus reducing the labor and time, and preserving the fibre, while at the same time treating the material 105 in a thorough and competent manner.

While the tank 14 is shown beneath the floor 11, it will be of course readily understood that this is more for the convenience of illustration, and that any suitable arrangement of any of the parts may be provided for and that modifications may be 110

made in the construction or parts without departing from the spirit of the invention as claimed.

Referring now more particularly to Fig. 5 2 it will be observed that instead of feeding the liquid tar directly from the tank 18' upon the fibrous material it may feed from said tank through a suitable pipe provided with a series of valves hereinafter referred 10 to and from the header 30 feeds into the barrels 31-32 and therefrom to the pipe 33 from which it is discharged by any suitable spray or discharge device through the pipe 34. The flow of the liquid tar or other im- 15 pregnating material from the tank 18' to the barrels 31-32 is controlled by the valves referred to, the valves 35-36 being float-valves suitably connected to the floats 37-38 for controlling the height of the 20 liquid in the barrels 31-32 and the valves 39-40 being suitably connected by rods or other suitable means 43-44 as shown to the valves 41-42 upon the outlet pipe 33 from which it will be seen that the predetermined 25 amount of impregnating liquid may be controlled for each bale of fibre treated. That is to say, when a bale is to be treated beneath the outlet 34 the valve 41 is opened, which being connected to the valve 39 automatically closes the same thereby allowing the liquid within the barrel 31 to escape 30 through the outlet 34. When the next bale is to be treated the valve 41 is closed thereby opening the valve 39 and allowing the

barrel 31 to refill. At the same time the 35 valve 42 is opened thereby automatically closing the valve 40 allowing the contents of the barrel 32 to be used, the barrel 31 having filled to the predetermined level again and having cut off its supply through 40 the valve 35 is now ready again to impregnate another bale and so on, thus providing suitable means for predetermining and regulating the amount of liquid tar or other material to be used in each bale. 45

The doors 7 may be omitted but the opening in the partition 9 is preferably closed while the cars are in the chamber 2.

I claim:

Means for treating successive masses of 50 fibrous material in a loose and unorganized state with predetermined quantities of treating material, comprising successive chambers into which said fibrous material is fed, means for charging said fibrous material 55 with said treating material in the first of said chambers, means for heating said fibrous material in the other of said chambers thereafter, and means in combination with said first chamber for charging the same 60 directly from the original container of said treating material.

In testimony whereof I hereunto affix my signature in the presence of two witnesses.

FRANK B. STRATFORD.

Witnesses:

ETHEL GARDNER,
THOMAS A. HILL.
